(57) **CLAIM**

We claim, the ornamental design for a developing apparatus for printer, as shown and described.

DESCRIPTION

FIG. 1 is a front perspective view of a developing apparatus for printer, showing our new design;
FIG. 2 is a front elevational view thereof;
FIG. 3 is a rear elevational view thereof;
FIG. 4 is a left side elevational view thereof;
FIG. 5 is a right side elevational view thereof;
FIG. 6 is a top plan view thereof; and,
FIG. 7 is a bottom plan view thereof.

The broken lines in the figures are for environmental purposes only and form no part of the claimed design.
